UNITED STATES PATENT OFFICE

109,034

DESIGN FOR A PARKING METER CASING

Robert Broussard and Charles A. Toce, Houston, Tex., and Charles Waltman, Chicago, Ill., assignors to Parkrite Corporation, Houston, Tex., a corporation of Texas

Application September 14, 1937, Serial No. 71,604

Term of patent 14 years

To all whom it may concern:

Be it known that we, Robert Broussard, Chas. A. Toce, and Charles Waltman, citizens of the United States, residing, respectively, in Houston, in the county of Harris and State of Texas, Houston, in the county of Harris and State of Texas, and Chicago, in the county of Cook and State of Illinois, have invented a new, original, and ornamental Design for Parking Meter Casings, of which the following is a specification, reference being had to the accompanying drawing, forming a part thereof.

Fig. 1 is a front elevation of a parking meter casing showing our new design.

Fig. 2 is a side elevation of the same.

Fig. 3 is a rear elevation of the same.

We claim:

The ornamental design for a parking meter casing substantially as shown.

ROBERT BROUSSARD.
CHARLES A. TOCE.
CHARLES WALTMAN.
